UNITED STATES PATENT OFFICE

2,114,175

ELECTRIC LAMP OR SIMILAR DEVICE

Paul O. Cartun, Cleveland Heights, Ohio, assignor to General Electric Company, a corporation of New York

Application March 13, 1937, Serial No. 130,713

7 Claims. (Cl. 176—29)

My invention relates to electric lamps and similar devices comprising a container or envelope having an energy translation element, such as a filament or electrodes, sealed therein. More particularly, my invention relates to tubular lamps or similar devices having a base at each end and still more particularly to such devices comprising a double walled container.

One of the objects of my invention is to provide a double walled electric lamp or similar device of simple and rugged construction. Another object is to provide a construction such that the two containers may be readily exhausted and, if desired, filled with a gas independently of each other. Another object is to provide an electric device of the type referred to in which the bases consist of metal discs sealed directly to the ends of the tubular glass containers as end walls and contacts, such as the construction shown and claimed in my Patent No. 2,032,791, of March 3, 1936. With such a construction, one of the said discs may serve as the end wall for both containers. Other objects and advantages of my invention will appear from the following description of species thereof and from the drawing.

In the drawing, Fig. 1 is an elevation, in section, of an incandescent lamp comprising my invention and Fig. 2 is a similar view of a gaseous discharge lamp.

Referring to Fig. 1, the lamp comprises an outer glass container 10 having a base member consisting of a metal disc 11 sealed directly to each end thereof as an end wall and contact. The particular discs 11 illustrated in the drawing are in this case identical and are of the type shown in my Patent No. 2,032,791, hereinbefore referred to. An inner glass container 12 is sealed at one end to the right hand disc 11 and has another base member or disc 13 sealed to its left hand end. Electrical contact is provided between the disc 13 and the left hand disc 11 by a spring 14 which is compressed between said discs. The inner container 12 has a filament 15 therein extending axially thereof. The said filament may be attached at its ends to short support wires 16—16 which are in turn secured to the wire end portions 17—17 of a stay which includes a glass rod 18. The extreme ends of said wire portions 17—17 are bent into transversely disposed loops 19 and 20 which engage the inner sides of shoulders 19 and 20 on the disc 13 and the right hand disc 11, respectively.

The inner container 12 is exhausted through an opening 21 at the center of the right hand disc 11, the said opening being subsequently sealed by

a glass mass 22 constituting the residue of the exhaust tube. The outer container 10 may also be exhausted and filled with a gas, if desired, through a similar opening 21 (not shown) in the left hand disc 11, the said opening being sealed by the glass mass 22. The lamp may be mounted by suitable holders engaging around the shoulders 20 on the discs 11—11.

The lamp may be assembled by first sealing the left hand disc 11 to the end of the outer container 10 and the disc 13 to the end of the inner container 12. The container 12 may then be placed in the container 10 with the spring 14 between the said discs 11 and 13. The mount, including the stay 18—17—17, supports 16—16 and filament 15, may then be inserted in the said container 12. Then the right hand disc 11 may be sealed to the ends of containers 10 and 12, the said mount being slightly compressed between the said disc 11 and the disc 13. The lamp is completed by evacuating the containers 12 and 10 through the right and left hand discs 11—11 respectively.

The lamp may also be assembled by first sealing the right hand disc 11 to the containers 12 and 10, inserting the mount, sealing the disc 13 to container 12 and then sealing the left hand disc 11 to the container 10 with the spring 14 in place. However, when this method is followed, care must be taken to avoid damaging the spring 14 by the sealing heat.

The construction of the discharge lamp shown in Fig. 2 is similar to the incandescent lamp in Fig. 1 except that electrodes 23—23 are substituted for the filament 15 and its supporting structure. The said electrodes may consist of tungsten wire coiled into a double helix with the primary mandrel remaining therein and having a coating of electron emissive material, such as barium oxide, thereon. The said electrodes may be welded at their ends to the disc 13 and the right hand disc 11. The inner container 12 may have a filling of a few millimeters of a rare gas such as argon or neon and may also contain a small quantity of metallic vapor 24, such as mercury. The outer container 10 may be evacuated or it may be filled with a gas adapted to conserve the heat in the inner container or with a cooling gas such as hydrogen or helium, or it may be left open to the atmosphere through the opening 21 (not shown) in the left hand disc 11.

While I have shown only two species of my invention, it will be obvious to those skilled in the art that various changes, substitutions and omissions may be made by those skilled in the art

without departing from the spirit of my invention. For example, the form of the discs 11—14—13 may be varied greatly. Discs of the type shown in the U. S. applications Nos. 3,334, H. D. Blake, filed January 24, 1935; and 75,772, G. E. Inman, filed April 22, 1936, may be used. The outer container 10 may be colored if desired. The left hand end of the inner container 12 may be further supported, for example by a perforated washer or other member surrounding the end of the said container 12 or the disc 13 and engaging the wall of the outer container 10 but permitting exhausting of the outer container if desired. The lamp may also be water cooled by fusing nipples to the ends of the outer container 12, or to the left hand disc 11 around the opening 21 and to the right hand disc 11 around an opening at a point between the outer and inner containers.

20 What I claim as new and desire to secure by Letters Patent of the United States is:

1. An electrical device comprising outer and inner glass containers, a common metal base member sealed to one end of both of said containers, a separate metal base member sealed to the opposite ends of each of said containers, means electrically connecting said last named base members, and an electric energy translation element within said inner container electrically connected to the said base members at the ends thereof.

2. An electrical device comprising outer and inner glass containers, a common metal base member sealed to one end of both of said containers and having a sealed exhaust opening communicating with said inner container, a separate metal base member sealed to the opposite ends of each of said containers, means electrically connecting said last named base members, and an electric energy translation element within said inner container electrically connected to the said base members at the ends thereof.

3. An electrical device comprising outer and inner glass containers, a common metal base member sealed to one end of both of said containers and having a sealed exhaust opening communicating with said inner container, a separate metal base member sealed to the opposite ends of each of said containers, the said one of the last named base members sealed to the outer container having a sealed exhaust opening therein, means electrically connecting said last named base members, and an electric energy translation

element within said inner container electrically connected to the said base members at the ends thereof.

4. An electrical device comprising concentrically arranged outer and inner tubular glass containers, a common metal base member sealed directly to one of the open ends of both of said containers, a separate metal base member sealed directly to the opposite open ends of each of said containers, means electrically connecting said last named base members, and an electric energy translation element within said inner container electrically connected to the said base members at the ends thereof.

5. An electrical device comprising concentrically arranged outer and inner tubular glass containers, a common metal base member sealed directly to one of the open ends of both of said containers and having a sealed exhaust opening communicating with said inner container, a separate metal base member sealed directly to the opposite open ends of each of said containers, means electrically connecting said last named base members, and an electric energy translation element within said inner container electrically connected to the said base members at the ends thereof.

6. An electrical device comprising concentrically arranged outer and inner tubular glass containers, a common metal base member sealed directly to one of the open ends of both of said containers and having a sealed exhaust opening communicating with said inner container, a separate metal base member sealed directly to the opposite open ends of each of said containers, the said one of the last named base members sealed to the outer container having a sealed exhaust opening therein, means electrically connecting said last named base members, and an electric energy translation element within said inner container electrically connected to the said base members at the ends thereof.

7. An electrical device comprising concentrically arranged outer and inner tubular glass containers, a common metal disc sealed directly to one of the open ends of both of said containers, a separate metal disc sealed directly to the opposite open ends of each of said containers, means electrically connecting said last named discs, and an electric energy translation element within said inner container electrically connected to the said discs at the ends thereof.

PAUL O. CARTUN.
